Filed June 13, 1962, Ser. No. 202,222
9 Claims. (Cl. 110—99)

This invention relates to apparatus for maintaining clean the tops of furnace walls, such as metallurgical furnaces and the like, constructed from suspended refractory bricks. This invention also relates to a way of suspending bricks in the roof of an open hearth or like metallurgical furnace.

This application is a continuation-in-part of application Serial No. 816,143, filed May 27, 1959, and now abandoned. Furnaces such as open-hearth furnaces and the like are usually constructed with a roof or top wall comprising suspended refractory bricks, and during operation of the furnace there is a gradual accumulation of undesirable loose debris on the roof which necessitates periodic cleaning by manual methods. The loose material insulates the roof and reduces its life.

The primary object of the present invention is to suspend refractory bricks at the roof of a metallurgical or like furnace by means including sturdy pipes which are disposed in close proximity to the top or cold ends of the roof bricks, and to enable these pipes to be used for cleaning of the top of the roof by arranging the pipes in communication with a line carrying air under pressure, and in some instances with suction. The pipes may extend for substantially the full length of the roof parallel to or concentric to the transverse shape of the roof, and will also be arranged in space relation for substantially the full length of the roof. Further, the pipes may be formed with openings in such a manner as to direct blasts of compressed air on to the top of the roof, and, where feasible, to withdraw the resultant disturbed debris through openings in those of the pipes which are connected with a suction line. However, I have found that the roof can be most effectively cleaned by compressed air alone and so emitted from the pipes in sequence back along the length of the roof as to move the debris from one end of the roof, along the length to the other end where it is to be disposed of. Merely shaking loose the debris by compressed air and creating a cloud of debris which will settle somewhere else in the general environment of the furnace installation is helpful; and the foregoing represent other objects of the invention.

In view of the fact that roofs of the kind under consideration are of a substantial width, it is important to provide for uniform action of the air under pressure flow, and another object of the present invention is to accomplish this. Many of the foregoing effects are made possible by a regulating valve provided for each of the brick-suspending pipes in order that variable conditions can be taken into account, and such represents another object of the present invention.

Other and further objects of the present invention will be apparent from the following description and claims and are illustrated in the accompanying drawings which, by way of illustration, show a preferred embodiment of the present invention and the principles thereof and what I now consider to be the best mode which I have contemplated for applying these principles. Other embodiments of the invention embodying the same or equivalent principles may be used and structural changes may be made as desired by those skilled in the art without departing from the present invention and the purview of the appended claims.

In the drawings:

FIG. 1 is a partial sectional view of an open-hearth

2

furnace having a roof constructed in accordance with the present invention;

FIG. 2 is a partial sectional view illustrating details of the brick-suspending pipes of the present invention;

FIGS. 3 and 4 are fragmentary elevations of the pipes taken substantially and respectively on the line 3—3 and 4—4 of FIG. 2;

FIG. 5 is another form of roof construction in accordance with the present invention;

FIG. 6 is a view on an enlarged scale of a portion of the longitudinal extent of the roof shown in FIG. 5;

FIG. 7 is an end view of a furnace constructed in accordance with another form of the present invention;

FIG. 8 is a detail sectional view of a portion of the roof structure shown in FIG. 7;

FIG. 9 is a side elevation of the roof illustrated in FIG. 7;

FIG. 10 is a sectional view on an enlarged scale of a portion of the roof shown in FIG. 9;

FIG. 11 is a sectional view illustrating another embodiment of the present invention; and

FIG. 12 is a fragmental elevation substantially on the line 12—12 of FIG. 11.

FIG. 1 of the drawing illustrates aspects of the present invention in relation to a typical section through an open-hearth furnace having the side walls SW and a roof R of refractory bricks which in most instances will be basic bricks 10 arranged in a suspended arch style, and the opposite ends of the roof R are backed up in a conventional manner by skew plate structure in turn arranged immediately above the side walls SW.

As is well known in the art, the main supporting structure or framework for an open-hearth furnace is afforded for the most part by structural beams, and this is particularly true insofar as the main support for the suspended roof R is concerned. Thus, horizontal steel beams 11 are so supported by upright beams 12 and 13 as to be spaced well above the back or so-called cold side of the roof defined by the tops of the bricks 10. Longitudinally extending beams 15 are supported in a conventional style at the underside of the main support beams 11, and roof supporting hook members 16 of varying lengths are secured to the longitudinal beams 15 to depend therefrom in the optimum spaced relationship.

Under the present invention, the bricks 10 are directly suspended by pipes 20 and 21 which will be described in more detail hereinbelow. It will be observed in FIG. 1 that the pipes 20 and 21 are in effect arcuate so as to be parallel or concentric to the shape of the roof R. These pipes have supporting plates 24 secured thereto in a rigid fashion as by welding, and the support plates 24 and the pipes 20 and 21, as will be observed in FIG. 1, extend for the full width of the roof R and are arranged in spaced parallel relation one behind the other for substantially the entire length of the roof R.

The brick elements 10 can, of course, be of variant composition and are advantageously encased in a rectangular steel casing 25 which has an extension 25E extending free of what will be the cold ends or top sides 10H of bricks 10 as shown in FIG. 2. Advantageously, hook-receiving openings 30 or like hook-receiving elements are provided at the sides of casing extensions 25E that will abut one another in pairs along the length of the roof in the assembled roof construction as shown in FIG. 2. Attaching brackets 31 are saddled on the tops of the pipes 20 and 21, and these brackets have spread legs 31L that extend downward from the fore and aft sides of the associated pipes. The lowermost ends of the legs 31L are bent upward at 31U, and the hooks thus afforded are connected into openings 30 of abutted or opposed casing extensions as shown in FIG. 2, thereby

suspending the bricks directly below the pipes 20 and 21 with the lowermost side walls of the pipes in close proximity to the tops or cold ends of the bricks. Such mode of suspension together with the extensions 25E afford channels C, FIG. 2, at the cold ends of the bricks, which channels extend from one side of the furnace to the other as will be apparent from FIGS. 1 and 2. This same relationship prevails with respect to the embodiment of the invention shown in FIGS. 5 and 6 hereinafter described.

The pipes 20 and 21 are formed with openings, and means are afforded to establish a forced air flow through the pipes which will be communicated to the top of roof R through such openings. Accordingly, the top of the roof R will be subjected to the disturbing influence of the air flow, and this is sufficient to in effect swirl any loose debris that has accumulated at the top of the roof. This of itself in some instances is sufficient to spread or spray the debris from the roof so that it settles on the surrounding floor area. In other instances, as will be apparent from the description to follow, the pipes can be sequenced by automatically controlled valves, so that the debris is moved progressively from one end of the furnace roof to the other in gradually increasing amounts.

Under the present invention, this air flow can be the joint action of air under high pressure and air under reduced pressure established by alternate ones of the pipes 20 and 21, or at least by selected of the pipes 20 and 21 as will now be explained.

Thus, under one form of the present invention, the pipes 20 are blower pipes and are formed with round openings 35, FIG. 2, arranged in spaced relation along the length of each pipe 20. The openings 35 are so oriented as to direct blasts of compressed air directly onto the tops of the bricks 10. The other pipes 21 are suction pipes, and these pipes have elongated openings 36 extended through the side walls thereof.

There are a pair of manifolds or headers 40 and 41, FIG. 1, which are to conduct air under high pressure, and additionally there are a pair of manifolds 42 and 43 representing the suction lines. These are located at the opposite side of the roof in an elevated position and extend parallel to the length of the roof, that is, at right angles, to the pipes 20 and 21. As shown in FIG. 1, flow of air is induced in the manifold 41 by connecting the same to a source HP of air under high pressure which can take different forms. Thus, the source HP can be a conventional air compressor, or a blower or the like, and preferably a regulating valve V1, which can be shut off, is interposed in the air line between the pressure source HP and the inlet end of the manifold 41. It is to be understood that the pressure manifold 40 at the opposite side of the furnace is also connected in like manner to a source of air under pressure.

The right-hand suction manifold 43 is connected to a standard vacuum source VU such as an exhaust pump, fan, or the like, and the system will, of course, include a filter or settling chamber effective to remove the debris carried by the air flow induced in the manifold 43 by the vacuum source VU. Again, a regulating valve V2, which can be shut off, is interposed between the vacuum source VU and the outlet end of the manifold 43, and it will be understood that a like arrangement is associated with the vacuum manifold 42 at the opposite side of the furnace. In such circumstances there would be no suction, but only pulses of air under pressure, themselves sufficient to accomplish a useful purpose as noted above and as will be evident hereinafter.

If desired, instead of affording separate sources HP and VU, there can be one source connected by a header in each instance to the inlet ends of the manifolds 40 and 41 and the outlet ends of the manifolds 42 and 43 respectively.

The pipes 20 that are to direct blasts of air onto the tops of the roof bricks are respectively connected adjacent their opposite closed or plugged ends to the pressure

manifolds 40 and 41. Such connections include stub pipes as 45 which are welded to the upper surfaces of the pipes 20 to be in communication therewith. The pipes 45 in turn are preferably connected to flexible hoses 46 or the like, and the hoses 46 in turn communicate with regulating valves V3 which can be shut off. The valves V3 in turn are connected to their pressure manifolds 40 and 41 by stub pipes of an appropriate size and dimension as shown in FIG. 1, depending of course upon space relations that are involved. Advantageously, the valves V3 can be solenoid valves capable of automatic sequencing as will be evident hereinafter.

It will be realized that the valves V3 can be set to regulate the rate of flow of compressed air through the connections to the pipes 20, and moreover, selected of these valves can be shut off to prevent entry of compressed air into selected of the pipes 20, depending upon the severity of conditions that may be encountered.

The suction pipes 21 are connected to their manifolds in a fashion substantially identical to the manner in which the pressure pipes are connected to their manifolds. Thus, stub pipes are welded to the upper sides of the suction pipes 21, adjacent the opposite closed ends thereof, and these in turn are in communication with flexible hoses 47 which in turn are connected to associated regulating valves V4, the valves V4 having stub pipe connections to the respective suction manifolds 42 and 43.

Another embodiment of the present invention is shown in FIGS. 5 and 6 in the form of a so-called held-up held-down roof. In this instance, the blower pipes and suction pipes 50 and 51, having openings as described above, are suspended by vertically disposed members formed to include threaded shanks 53 which have the lower ends thereof retained by nuts and bolts in stub sockets 52 that in turn are saddled on and welded to the top sides of the aforesaid pipes at suitable spaced locations. The shanks in turn are locked by nuts to supporting beams.

The bricks in this embodiment are also encased in metallic housing plates which have extensions formed with anchor openings in which are received hook arms 57 that in turn are saddled on and hung from the pipes 50 and 51 as above described. Thus, the bricks again are suspended below the pipes, and the air-conducting pipes are centered above the opposed casing extensions as 25E in selected rows of bricks. The pressure pipes 50, as shown in FIG. 5, have their ends in communication with inlets 60 for air under pressure, these inlets in turn being in communication with a compressed air manifold 61 through a manual regulating valve 62. Like connections and valving are afforded between suction manifolds 65 and the suction pipes 51 to enable suction to be created, if desired, on the tops of the bricks, and the manifolds 61 and 65 are connected to suitable sources as described above.

Advantageously, the bricks at selected locations are stabilized by large rectangular plates 67 having lower ends substantially flush with the hot or lower ends of the bricks. The upper ends of these plates are removably secured in place, as by nuts and bolts, between a pair of supporting flanges 68 that are welded to and depend from the lower sides of the pipes 50 and 51. Thus, the plates 67 are spaced or interposed between every four bricks along the longitudinal dimension of the roof as shown in FIG. 6, which is also the spacing of the pipes 50 and 51 along the longitudinal extent of the roof, and as shown in FIG. 5 the plates 67 have a width of about six bricks across the lateral span of the roof arch, noting that the pipes 50 and 51 span the width of the roof.

In FIGS. 7 to 10, another form of roof construction within the purview of the present invention is illustrated, and in this instance the roof RR is of the arch type, when viewed transversely, and has a front to rear downward slope as is evident in FIG. 9. As in the foregoing embodiment, the bricks at the ends of the arch bear against skew plates 100 and 101.

Upright columns 105 and 106 are arranged at the op-

posite sides of the furnace and have ends projecting upwardly above the outer or cold end of the roof structure as shown in FIG. 7. These uprights are spanned by horizontal beams 110 which in turn are supported by inclined braces 112 and 113 which have ends respectively secured to the uprights 105 and the cross-beams 110.

Channel beams 120, FIG. 7, which extend for the length of the roof, repose on the cross beams 110 as best shown in FIG. 9, and the upper surfaces of the channels 120 carry plates 122 which are secured thereto by welding. The plates 122 serve to support nuts 125 that are threaded on the uppermost ends of vertical support bolts 126 which are disposed within apertures in the plates 122 to hang therefrom. There are many such plates 122 and bolts 126 as illustrated in FIG. 9. The bolts are of increasing length proceeding from the front to the rear of the roof, this being in accordance with the front to rear slope of the roof RR.

The lower ends of the supports 126 are also threaded, and are extended through openings in anchor plates 130 which in turn are secured to channel beams 135 in the manner illustrated in FIG. 9. The channel beams are therefore supported generally in a plane inclined in accordance with the slope of the roof RR.

The channels 135 serve to support directly the suspending tubes or pipes 139 which in turn are arranged in accordance with the present invention to allow the bricks to be cleaned of debris at the cold ends thereof, while at the same time enabling the bricks to be supported advantageously in a stabilized manner.

Thus, the pipes 139, as shown in FIG. 7, are bowed to conform to the roof arch, being concentric to the transverse shape of the roof RR, in order that the bricks will be uniformly acted upon when air under pressure is provided as will hereinafter be explained. The pipes 139 are spaced one from another in a front to rear relationship along the length of the roof as will be evident in FIG. 9.

The pipes or tubes 139 are of course hollow and are spaced slightly above the upper cold ends of the bricks 140. The pipes are provided with apertures 139A and 139B, FIGS. 8 and 10, so oriented one with respect to another as to direct jets of compressed air downwardly onto the tops or cold ends of the bricks 140 in order to facilitate removal of debris or loose refractory that has accumulated at the top of the roof.

The bricks are supported in the manner explained above in connection with the first embodiment of the invention. Thus, each brick 140 includes a core 140C of refractory material and a metallic casing of steel or like ferrous alloy 140M which surrounds all four sides of the brick. The metallic casing includes at least two tabs 144 and 145, FIG. 10, which extend beyond the free or cold end of the refractory core 140C and these tabs or ears are provided with openings 144A and 145A in which can be inserted the hooked ends 141 and 142 of a support wire 150 which is bent over to be supported by the pipes as 139. Thus, the supporter or hanger 150 is substantially of inverted V-form including a pair of outwardly extending leg elements having the hook portions 141 and 142 at the free ends thereof, and these hook portions are used to hold the projecting ends of the abutting metallic casings that surround adjacent ones of the bricks. It will be appreciated from FIG. 9 that there need be a pipe as 139 for every four bricks since each hooked end of the support 150 will support a pair of bricks.

In order to stabilize the roof and to assure further rigidity during actual operation as may be occasioned by the oxidation involved, relatively large stabilizer plates 155 are hung from the pipes 139 so as to be disposed between an adjacent pair of bricks considered in a front to rear sense. To this end, flange plates 153 and 154 are welded in spaced, depending relation to the underside of each pipe 139. The flange plates are used to support a pair of nuts and bolts N1 and N2, FIG. 8, which extend normal to the planes of the plates 153 and 154 to

serve as supports for the stabilizer plates 155. Thus, the stabilizer plates 155 are of rectangular shape, and at the upper edge thereof are formed with bayonet slots S1 and S2 which enable the stabilizer plates to be moved upwardly past the bolt assembly N1 and N2 and then shifted to the left or right, however viewed, to present the right angled legs of the slots S1 and S2 to the supporting bolt assembly N1 and N2. It will be appreciated that this is accomplished as a preliminary assembly prior to the bricks 140 being put in place.

Air under pressure is furnished to the pipes 139 by a header or manifold 165 which has supply tubes, hoses or the like 166 in communication therewith and connected to normally closed solenoid valves as 168. The output side of each valve 168 is connected by a conduit 169 or the like to a related one of the pipes 139 substantially at the mid-point of the length thereof as shown in FIG. 7. The pipes 139 have dead ends and consequently, when a valve 168 is opened, air under pressure in the manifold 165 rushes into the pipe 139 and emits in jet streams through the openings 139A and 139B.

The foregoing arrangement enables the pipes 139 to be sequenced since the valves 168, being of the solenoid type, can be operated remotely and automatically and, by proper timing, in any desired sequence and rate. Thus, for example, the valve 168 to be associated with the first or forwardmost one of the pipes 139 could be actuated or opened first for a brief duration, then the valve for the next pipe and the valve for the next pipe, and so on down the line timed to move a cloud of debris gradually from the front of the furnace to the rear.

The pipes 170, shown in FIG. 12, in turn are carried by elongated U-straps 171 having the free ends of the legs 170L thereof threaded. The threaded ends of the straps 171 are extended through anchor plates 172 supported by beams BL and nuts 171N are provided on the ends of the legs 170L that project above the plate 172.

In FIGS. 11 and 12 another embodiment of the present invention is illustrated in association with a refractory roof RR' which is flat rather than arcuate. Here, the bricks 160 which afford the roof RR' are of the basic type encased in metallic sleeves 160M as in the foregoing embodiment. These sleeves or casings include extensions 160E provided with apertures which receive the hooked ends 164 and 165 of support wires 166 which in turn are supported by and depend from pipes 170 adapted to carry air under pressure.

As in the foregoing embodiment the pipes 170 are parallel to the transverse shape of the roof and are provided with apertures which will direct jet streams of compressed air on to the tops or cold ends of the bricks to remove debris therefrom in the manner described above.

It may be noted, however, that in this instance of the flat roof of the pipes 170, as shown in FIG. 11, advantageously extend from a remote side of the roof approximately to the mid-point of the roof where the pipe is capped at 170C to afford a dead end. A similar pipe 170 having a dead end cap 170C-1 extends from the mid-point of the roof as viewed in FIG. 11 to the right-hand (not visible) remote side of the roof.

Each such pipe 170 at its uncapped end communicates with a hose 173 which communicates in turn with a manifold 175 through a valve 177 adapted to be sequenced in the manner described above to gradually move a cloud of debris step-by-step from the front of the roof to the rear or, for that matter, in the opposite direction, depending upon the nature of the installation.

It will be seen from the foregoing that the present invention makes it possible to remove debris from the top of the roof of a furnace afforded by basic refractory bricks, and at the same time the invention affords a convenient way of suspending the bricks while making provision for the installation of stabilizer plates. Hence, while I have illustrated and described preferred embodiments of my invention it is to be understood that these are capable of variation and modification, and I there-

fore do not wish to be limited to the precise details set forth, but desire to avail myself of such changes and alterations as fall within the purview of the following claims.

I claim:

1. In a furnace of the kind described, a suspended roof of refractory bricks subject to accumulations of debris during use of the furnace, means for suspending said bricks including a plurality of spaced brick-supporting pipes disposed over the tops of the bricks in close proximity thereto, selected of said pipes being connected to a source of air under pressure, and said pipes having spaced openings in the walls thereof throughout substantially the entire length thereof enabling blasts of air under pressure to be directed onto the tops of said bricks, incidental to loosening and removing the debris from the tops of the bricks.

2. In a furnace of the kind described, a suspended roof of refractory bricks subject to accumulations of debris during use of the furnace, means for suspending said bricks including a plurality of spaced brick-supporting pipes disposed over the tops of the bricks in close proximity thereto, said pipes being arranged substantially in parallel relation one to another, said pipes extending for substantially the full transverse width of the roof and being spaced throughout substantially the full longitudinal extent of the roof, said pipes having spaced openings in the walls thereof throughout substantially the entire length thereof and in close proximity to the tops of the bricks to effectively direct jets of air thereagainst, and said pipes being connected to a manifold which in turn is connected to means for creating a forced flow of air through said manifold and pipes to create a disturbing air flow on the tops of said bricks to loosen accumulations of debris collected thereon.

3. A furnace according to claim 2 wherein regulating valves means are interposed between said manifold and pipes.

4. A furnace according to claim 3 wherein the valve means are automatically sequenced to produce gradual loosening of the debris step-wise through the pipes from one end of the roof to the other.

5. In a furnace, a suspended roof spanning a pair of side walls and being constructed of transverse rows of refractory bricks which rows extend from one side of the furnace across the width of the roof to the other side, said bricks having hot lower ends that face the combustion area of the furnace and said bricks having cold upper ends that define the top of the roof, the cold ends of the bricks being subject to gradual deterioration during use of the furnace whereby refractory debris tends to accumulate at the top of the roof, a plurality of air-conducting pipes disposed over the cold upper ends of the bricks in close proximity thereto, said pipes being spaced throughout the length of the roof so that several rows of bricks across the width of the roof lie between adjacent pipes, said bricks each having a refractory core and a metallic casing extending thereabout, said casings having projections at the cold ends of the bricks that extend beyond the cold ends of the refractory cores to be free thereof and which are in abutting back-to-back relationship across the width of the roof to afford channels that extend across the arch of the roof, hangers secured to said pipes and having leg portions depending below said pipes on opposite sides thereof, said leg portions of the hangers being secured to abutted casing extensions on opposite sides of the pipes whereby each of the hangers on each pipe is effective to suspend several bricks between adjacent pipes, said pipes each having spaced openings therein substantially uniformly throughout the length thereof for communicating air flow in the pipes to the tops of the bricks to swirl and disturb any debris thereon, and means connected to said pipes for creating at will a forced flow of air therethrough to be communicated to

the tops of said bricks through the openings in said pipes as aforesaid.

6. In a furnace, a suspended arch-shaped roof spanning a pair of side walls and being constructed of transverse rows of refractory bricks which rows extend from one side of the furnace across the width of the roof to the other side, said bricks having hot lower ends that face the combustion area of the furnace and said bricks having cold upper ends that define the top of the roof, the cold ends of the bricks being subject to gradual deterioration during use of the furnace whereby refractory debris tends to accumulate at the top of the roof, a plurality of air-conducting pipes disposed over the cold upper ends of the bricks in close proximity thereto and each of said pipes being of arcuate form to be substantially concentric to the arch of the roof, said pipes being spaced throughout the length of the roof so that several rows of bricks lie between adjacent pipes, said bricks each having a refractory core and a metallic casing extended thereabout, said casings having projections at the cold ends of the bricks that extend beyond the cold ends of the refractory cores to be free thereof and which are opposite one another in rows across the span of the roof, said pipes being spaced throughout the length of the roof so that several rows of bricks across the arch lie between adjacent pipes and so that the pipes are centered above selected rows of the opposed casing extensions, hangers secured to said pipes and having leg portions depending below said pipes on opposite sides thereof, said leg portions of the hangers being secured to opposed casing extensions on opposite sides of the pipes whereby each of the hangers on each pipe is effective to suspend several bricks between adjacent pipes, stabilizer plates secured to and depending from said pipes and being disposed between the casings having opposed extensions above which the pipes are centered as aforesaid, said pipes each having spaced openings therein substantially uniformly throughout the length thereof for communicating air flow in the pipes to the tops of the bricks to swirl and disturb any debris thereon, and means connected to said pipes for creating at will a forced flow of air therethrough to be communicated to the tops of said bricks through the openings in said pipes.

7. In a furnace, a roof spanning a pair of side walls and being constructed of transverse rows of refractory bricks which rows extend from one side of the furnace across the arch to the other side, said bricks having hot lower ends that face the combustion area of the furnace and said bricks having cold upper ends that define the top of the roof, the cold ends of the bricks being subject to gradual deterioration during use of the furnace whereby refractory debris tends to accumulate at the top of the roof, a plurality of air-conducting pipes disposed over the cold upper ends of the bricks in close proximity thereto, said pipes being spaced throughout the length of the roof so that several rows of bricks across the arch lie between adjacent pipes, said bricks each having a refractory core and a metallic casing extended thereabout, said casings having projections at the cold ends of the bricks that extend beyond the cold ends of the refractory cores to be free thereof and which are in opposed relationship across the span of the roof, hangers secured to said pipes and having leg portions depending below said pipes on opposite sides thereof, said leg portions of the hangers being secured to opposed casing extensions on opposite sides of pipes whereby each of the hangers on each pipe is effective to suspend several rows of bricks between adjacent pipes, said pipes each having spaced openings therein substantially uniformly throughout the length thereof for communicating air flow in the pipes to the tops of the bricks to swirl and disturb any debris thereon, and means connected to said pipes for creating at will a forced flow of air therethrough to be communicated to the tops of said bricks through the openings in said pipes as aforesaid, the last-named means including manifolds connected to said pipes and means for supply-

ing air under pressure in controlled amounts to said manifolds.

8. In a furnace, a suspended roof spanning a pair of side walls and being constructed of transverse rows of refractory bricks which extend from one side of the furnace across the arch to the other side, said bricks having hot lower ends that face the combustion area of the furnace and said bricks having cold upper ends that define the top of the roof, the cold ends of the bricks being subject to gradual deterioration during use of the furnace whereby refractory debris tends to accumulate at the top of the roof, a plurality of air-conducting pipes disposed over the cold ends of the bricks in close proximity thereto, said pipes being spaced throughout the length of the roof so that several rows of bricks across the arch lie between adjacent pipes, means secured to said pipes and suspending several bricks in each row on opposite sides of each pipe, said pipes each having spaced openings therein substantially uniformly throughout the length

thereof for communicating air flow in the pipes to the tops of the bricks to swirl and disturb any debris thereon, and means connected to said pipes for creating at will a forced flow of air therethrough to be communicated to the tops of said bricks through the openings in said pipes as aforesaid.

9. A furnace according to claim 8 wherein the last-named means includes manifolds connected to said pipes and means for supplying air under pressure in controlled amounts to said manifolds.
